UNITED STATES PATENT OFFICE.

DAVID J. CANCHESTER, OF CHICAGO, ILLINOIS.

BURNER FOR LIQUID HYDROCARBONS.

SPECIFICATION forming part of Letters Patent No. 746,283, dated December 8, 1903.

Application filed December 16, 1902. Serial No. 135,380. (No model.)

To all whom it may concern:

Be it known that I, DAVID J. CANCHESTER, a citizen of the United States, residing in the city of Chicago, county of Cook, and State of Illinois, have invented a new and useful Improvement in Burners for Liquid Hydrocarbon, of which the following is a specification.

My invention relates to burners for liquid hydrocarbon, and has for its object, first, to provide means for distributing the liquid hydrocarbon within the vaporizer to facilitate vaporization; second, to provide means for precipitating impurities of the hydrocarbon and preventing the access of said impurities to the valves and burner; third, to provide a receptacle for retaining said impurities, which receptacle may be readily removed and cleansed or renewed; fourth, to provide means for keeping the passage in the needle-valve clear of obstructions; fifth, to provide means for adjusting the globe, and, sixth, to provide the other details hereinafter set forth. I attain these objects by the mechanism illustrated in the accompanying drawings, in 25 which—

Figure 1 is a general view, partly in vertical section, showing a lamp-burner embodying my invention. Fig. 2 is a view of the vaporizer shown in position in its supporting socket. Fig. 3 is a sectional view of the vaporizer. Fig. 4 is a fragmentary view showing the method of operating the valve-spindle. Fig. 5 is a vertical sectional view of the burner and of the globe-holder and its supports. Fig. 6 is a transverse sectional view of the vaporizer on the line 6 6, Fig. 3.

Similar reference characters denote similar parts throughout the several views.

The inlet-valve seat *a* is connected to the supply-pipe *b* by means of the coupling *b'* and is connected to the cylindrical vaporizer-casing *c* by means of the coupling *a'*. The inlet-valve *d* seats upon said valve-seat and spreads toward the bottom for the purpose of distributing the hydrocarbon as it enters the vaporizer. Said valve is formed at the upper extremity of the valve-stem *e*; and said valve-stem is raised and lowered by means of the rack *e'* thereon, which is engaged by the pinion *f*. Said pinion is secured on the spindle *f'* by means of the nut *f''* and is rotated by

said spindle. Said spindle enters the vaporizer-casing *c* through the stuffing-box *e''* on said casing.

The settling-well *g* is a vessel consisting, 55 preferably, of two concentric cylinders completely joined at the bottom and open at the top, the outer cylinder fitting within the vaporizer-casing *c* and resting upon the shoulder *c'*, formed at the bottom of said casing 60 where joined with the tubular extension *c''* of the casing. By preference the outer cylinder of said well is of an equal height with the casing *c*, while the inner cylinder is of a height somewhat less, in order to permit the hydrocarbon to flow over the top thereof. The diameter of the valve-stem *e* is less than the inner diameter of the settling-well, thereby affording a passage for hydrocarbon therebetween.

A cylindrical separator *h*, equal in height with the casing *c*, is placed concentrically within said casing and is of such a diameter as to occupy a position between the inner and outer cylinders thereof. Said separator is 75 closed at the top except where it receives the valve-stem *e*, and consequently there is a passage between the top of said separator and the top of the inner cylinder of the settling-well. Said separator rests upon the bottom 80 of the settling-well, but is provided with apertures *h'* near the bottom, which afford a passage for the hydrocarbon. The greatest diameter of the valve *d* is approximately as great as the diameter of said separator, and 85 in operation the hydrocarbon is distributed by said valve *d* to the chamber between the separator and the outer cylinder of the settling-well. Strainers *i i* are provided in the settling-well *g* for preventing as far as possible foreign material from entering the interior parts of the device.

In order to hold the separator *h* in its proper position within the well, said separator is provided with the spacing-wings *h'' h'''*, as best 95 shown in Fig. 6. The flange or foot *h''* is formed at the bottom of the separator *h* and constitutes a false bottom to the settling-well. Another purpose of said wings is for cleaning the settling-well *g*. This is accomplished by 100 rotating said separator by hand, which causes said wings to scrape the sides of the

well and remove any matter which may have adhered thereto. The settling-well *g* and separator *h* do not require to be fastened in position, and on account of their simple construction counterparts may be readily substituted. As these parts of the vaporizer are the ones most liable to become clogged, the proper renewal of these parts will indefinitely prolong the life of the device.

10 The vaporizer-casing *c* slips into and is supported by the socket *j*, which in the present instance comprises the rings *j'* and *j''*, suitably connected together, so as to retain said casing and the parts attached thereto. At 15 the upper extremity of said socket is formed a shield *j'* for preventing the heat of the burner from damaging the upper extremity of the casing. The flanged periphery of said shield is apertured to receive the rods *k* *k*, whereby said socket and its appendages are suspended. A set-screw *j'* is provided in the ring *j''* for securing said casing *c* in position. Said shield is also provided with arms *j''* for suspending the mantles *m*. The ring *j''* is 25 rigidly suspended from the socket *j* and is interiorly threaded to be coupled with the mixing-chamber *n*, hereinafter described. The extension *c'*, screw-connected with the lower extremity of the casing *c*, is coupled at its 30 lower extremity to the needle-valve seat *o*. Within said extension is placed the lining-tube *o'*, which is screwed into the lower extremity of the inner portion of the settling-well *g*. The purpose in providing the said lining-tube attached to said settling-well is to afford a ready means for keeping the passage around the valve-stem *e* clean. If said extension becomes clogged, it may be withdrawn by lifting out the well *g* and then unscrewing 35 said lining-tube and either cleansing the same or substituting a new tube in lieu thereof. The valve-stem *e* extends downward through said tube *o'* and at its lower extremity forms a valve for closing said valve-seat *o*. The latter is chiefly for emergency use—to quickly 40 shut off the supply of vapor from both burners and extinguish the flame. When thus used, as soon as combustion has ceased the valve-stem may be raised and the valve *d* 45 closed, thus preventing the settling-well from becoming filled with liquid. A wire *p* is attached to the lower extremity of the stem *e* in such a manner as to pass through the needle-aperture in the seat *o* and is of an exceedingly 50 small diameter, so as to permit the passage of vapor through the valve-seat when said wire occupies a position therein—that is to say, said wire does not completely fill the aperture in the valve-seat *o*. By this construction the rotation of the spindle *f* not only 55 opens and closes the valve-seats *a* and *o*, but also cleans the latter by working up and down and loosening any obstructing material which may have adhered to the sides of the aperture 60 therein. It will thus be seen that the valve-stem *e* and its adjuncts have three separate functions—first, to control the supply of liq-

uid entering the vaporizer; second, to operate as an emergency-valve, and, third, to afford means for cleaning the valve-seat *o*.

70 The mixing-chamber *n* screws into the ring *j''* and is provided with a series of apertures *p'* for admitting the air. Said mixing-chamber has a shoulder *n'* formed thereon for supporting the preheating-cup *q*. Said cup is 75 loosely mounted on said mixing-chamber, so as to be revoluble on said shoulder *n'*, and is provided with a series of apertures *q'* for regulating the supply of air through the apertures *p'* in the chamber *n*. Said cup is controlled 80 by means of the rod *r*, and the parts are so related that the valve-seat *o* discharges into the mixing-chamber *n* above the air-apertures *p*.

85 The burner-pipes *s* screw onto the lower extremity of the mixing-chamber *n* and extend upward, so that the mouths thereof are somewhat below the vaporizing-casing *c*. The mouths of said pipes are, however, close enough to said casing to heat the same to a 90 degree sufficient to vaporize the hydrocarbon entering thereinto. The flames issuing from the mouths of said pipes *s* will also heat the exposed tubular extension *c'*. A valve *s'* is 95 provided in each of said pipes for shutting off the supply of vapor to the burners when desired. At the mouths of said pipes are placed the spreaders *s''* *s'''*, and the gauzes *s''* are also desirable at said mouths. At the lower extremity of said burner-pipes is the interiorly-screw-threaded boss *t*, which receives and supports the downwardly-extending rod *u*. At its lower extremity said rod screws into the socket *v'* of the handle *v*.

100 The globe-holder *w* is provided with the annular groove *w'* for receiving the lower extremity of the globe *x* and is also provided with the sleeve portion *w''*, which incloses the rod *u* and is of a sufficient interior diameter to inclose the handle *v*. A shoulder *w''* is 110 formed at the upper extremity of said sleeve for engaging the upper edge of the socket *v'* when the globe-holder is lowered. A set-screw *w'* is provided in said holder for securing the same at any desired height on the rod *u*. 115 Thus the parts are so arranged that when it is desired to renew the mantles *m* the holder *w* may be lowered until the shoulder *w''* rests upon the socket *v'*; but under normal conditions the globe may be held at any height desired.

120 It is desirable to provide means for removing liquid which from any cause may collect at the bottom of the burner-pipes *s*. For this purpose an annular recess *u'* is formed at the upper extremity of the rod *u*. In case liquid collects in said pipes *s* said rod is unscrewed from the boss *t* and lowered a slight distance, and the liquid may then pass out through the 125 passage thus opened. In order to suspend said rod *u* at the right height to permit the escape of liquid and at the same time prevent the upper extremity of said rod from leaving said boss, both said boss and rod are provided with 130

pins y y , which are adapted to be engaged by the links or hooks z . By this construction there is no danger of the rod u becoming entirely detached at the risk of breaking the globe x .

5 The stack A is suspended above the mantles by any suitable means and carries the shade-holder B for supporting the shade C in the usual manner.

10 In operation when the valve d is open liquid hydrocarbon enters from the pipe b and is spread by said valve, so as to enter the settling-well g outside of the separator h . Said well and the casing c are hot, being heated at 15 starting by flames from the preheating-cup q and subsequently by flames from the burner-pipes. The hydrocarbon upon entering said hot settling-well and being distributed to all portions thereof by said valve is more or less 20 completely vaporized at once and passes to the bottom of said well, thence through apertures h' at the lower extremity of the separator h , thence upward inside of said separator, over the top of the inner wall of the settling-well, and thence downward through the 25 needle-valve o to the mixing-chamber n , finally emerging from the mouths of the burner-pipes, where vaporization is complete and ignition takes place. The motion of the 30 liquid downward in the settling-well g is slow, for the reason that the passage outside of the separator h is comparatively large. This permits the impurities, which are of greater specific gravity than the hydrocarbon, to settle 35 at the bottom of said well and there remain, being uninfluenced by the slowly-upward-moving current inside of said separator.

If the needle-valve seat o is obstructed, the 40 stem e is raised and lowered a few times, whereupon the wire p will dislodge the obstructions and permit a free flow. When impurities have collected to an extent sufficient 45 to clog the passages, the nut f^2 is unscrewed from the spindle f' and the latter withdrawn to permit the disassembling of the parts. After the stem e is removed the settling-well g is withdrawn from the casing c , bringing with it the separator h and lining-tube o' . The 50 tube is then unscrewed and cleansed or renewed, and the separator is rotated within the well g , the wings h^2 acting as scrapers. This loosens the obstructions in said well, and the foot or flange h^3 will carry with it the obstructions upon the withdrawal of the separator h from said well.

55 It will be understood that the construction of many of the parts described may be varied without departing from my invention. The essential features are pointed out in the accompanying claims.

Having thus described my invention, what I claim as new, and desire to secure by Letters Patent, is—

60 1. In a burner for liquid hydrocarbon, a settling-well consisting of two concentric cylinders connected together at the bottom and open at the top; a cylindrical separator open at

one end and closed at the other end and placed in an inverted position within said well, said separator having a passage at the bottom thereof and being of sufficient height to afford a passage between the top thereof and the inner wall of the settling-well; means for distributing the liquid to the settling-well outside of the separator; a needle-valve seat 70 connected to said settling-well; and a valve-stem coöperating therewith.

2. In a burner for liquid hydrocarbon, a settling-well open at the top and having a passage extending downward through the middle 80 to the burner; a separator open at one end and closed at the other end and placed in an inverted position within said well, there being a passage as h' between the bottom of said separator and the bottom of said well, 85 and there being also a passage between the top of the separator and the top of the inner wall of the settling-well to permit the flow; and means for distributing the liquid to the settling-well outside of the separator. 90

3. In a burner for liquid hydrocarbon the combination of a vaporizer-casing, a settling-well in said casing, a separator fitting loosely in said well, and a foot on said separator forming a false bottom to said well for removing obstructions therefrom. 95

4. In a burner for liquid hydrocarbon, the combination of a vaporizer-casing, a cylindrical settling-well in said casing, a cylindrical separator in said well, and wings on 100 said separator, said separator-wings scraping the walls of said well when said separator is rotated.

5. In a burner for liquid hydrocarbon, the combination of a vaporizer-casing, a tubular 105 extension of diminished diameter depending therefrom, a settling-well fitting loosely in said casing, said well being hollow and forming passages for hydrocarbon both inside and outside of its inner wall; and a lining-tube 110 secured to the bottom of said well and fitting into said tubular extension, said lining-tube connecting with the passage inside of the inner wall of said well for the purpose described. 115

6. In a burner for liquid hydrocarbon, the combination of a settling-well, a separator fitting loosely in said well, a foot on said separator forming a false bottom to said well for removing obstructions therefrom, a needle-valve seat connected to said well, an outlet-valve coöperating with said seat, an inlet-valve seat, and an inlet-valve controlling the same, said inlet-valve and outlet-valve being formed on the same stem on opposite extremities thereof. 120

7. In a burner for liquid hydrocarbon, the combination of a settling-well, a separator fitting loosely in said well, a foot on said separator forming a false bottom to said well for removing obstructions therefrom, a needle-valve seat connected to said well, an outlet-valve coöperating with said seat, an inlet-valve seat, an inlet-valve controlling the same, said inlet-valve and outlet-valve being 130

formed on the same stem on opposite extremities thereof, a rack formed on said stem and a pinion for operating said rack.

8. In a burner for liquid hydrocarbon, the combination of a settling-well, a separator fitting loosely in the well, a foot on said separator forming a false bottom to said well for removing obstructions therefrom, a mixing-chamber for receiving vapor from the settling-well, a boss formed at the bottom of the mixing-chamber, a threaded rod or plug screwing into said boss and having an annular recess formed at its upper extremity for permitting the escape of liquid from said mix-

ing-chamber when said rod or plug is partially withdrawn from said boss.

9. In a burner for liquid hydrocarbon, the combination of a heated settling-well, open at the top, an inlet-valve seat above said well, and a valve for closing said valve-seat, said valve having a tapered or flaring head for distributing the liquid to all portions of the well for facilitating vaporization.

DAVID J. CANCHESTER.
